[57] CLAIM

The ornamental design for a flexible flying disk toy, as shown and described.

DESCRIPTION

FIG. 1 is a perspective view of a flexible flying disk toy, taken from above, showing my new design;

FIG. 2 is a side elevation thereof;

FIG. 3 is a bottom plan view thereof, it being understood that the ribbing and surface texture continue over the entire structure; and,

FIG. 4 is a sectional view taken along the line 4—4 in FIG. 3.

*FIG. 1.**FIG. 2.*FIG. 3.

FIG. 4.
